U.S. Appl. No. 15/603,070, filed May 23, 2017.

Primary Examiner — Holly E Thurman*Assistant Examiner* — Leisha N Prie(74) *Attorney, Agent, or Firm* — Barnes & Thornburg LLP(57) **CLAIM**

What is claimed is the ornamental design for a rotational coupler, as shown and described.

DESCRIPTION

FIG. 1 is a perspective view as viewed from above the rotational coupler showing our design;

FIG. 2 is a perspective view as viewed from below thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a top plan view thereof; and,

FIG. 8 is a bottom plan view thereof.

The broken lines in the drawings illustrate portions of the rotational coupler and form no part of the claimed design. The dot-dot-dash broken lines in the drawings define the bounds of the claim and from no part thereof.
